(57) **CLAIM**

The ornamental design for a combined motorized broom and collector, as shown and described.

DESCRIPTION

FIG. 1 is a perspective view of a combined motorized broom and collector in accordance with the present invention in a sweeping position.

FIG. 2 is a front elevation view of FIG. 1.

FIG. 3 is a left side elevation view of FIG. 1.

FIG. 4 is a top plan view of FIG. 1.

FIG. 5 is a bottom plan view of FIG. 1.

FIG. 6 is a right side elevation view of FIG. 1.

FIG. 7 is rear elevation view of FIG. 1; and,

FIG. 8 is a perspective view of a motorized broom and collector in accordance with the present invention with the broom in a collection position.
